FIG. 2

FIG. 4

FIGURE 1 is a front elevational view of a covered casserole dish or the like embodying my new design.

FIGURE 2 is a side elevational view.

FIGURE 3 is a top plan view.

FIGURE 4 is a fragmental cross-sectional view in elevation taken along a portion of line 4-4 of FIGURE 3, with the surface decoration greatly enlarged to illustrate the texture thereof.

My design for a covered casserole dish or the like is characterized by a plurality of spaced annular grooves having color and surface character contrasting with that of the remainder of the body surface, in the arrangement and having the configurations substantially as shown.

I claim:

The ornamental design for a covered casserole dish or the like, as shown and described.
